CLAIM

The ornamental design for a server for data, as shown and described.

DESCRIPTION

FIG. 1 is a front elevational view of a server for data showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a first perspective view thereof; and,

FIG. 8 is a second perspective view thereof.

The present article is a server for data having a printer function. When a cover provided on the rear surface of the present article is opened, a sheet of paper can be inserted thereto. The present article can be used as a printer using a touch panel monitor provided on the front surface of the present article. A printed sheet of paper is discharged from an outlet provided in a lower surface of the touch panel monitor.
